JOINTS OF WALLS, ROOFS, AND THE LIKE
CONSTRUCTED FROM PREFORMED PANELS OR SLABSBernard Brunton and Rolfe Gilbert Booth,
London, EnglandApplication July 14, 1943, Serial No. 494,714
In Great Britain April 22, 1942

4 Claims. (Cl. 20—4)

This invention relates to the joints of walls, roofs and the like constructed from preformed panels or slabs. The invention is particularly concerned with the walls and roofs of huts and like buildings constructed from preformed panels or slabs, and objects of the invention are to provide for rapid erection or building of the wall or roof and to ensure of same being built to accurate dimensions, and in the case of a three- or four-way wall junction to ensure proper location of all of the walls at the said junction. Further objects of the invention are to ensure that a tight and satisfactory joint will be obtained and to achieve these results without having to employ highly skilled labour.

According to the invention a wall or roof is built from preformed panels or slabs, the mutually-opposed edges of which are separated by a spacing element, and there is or are provided one or more cover pieces through which holes are formed, in the course of manufacture of said cover piece or pieces, said holes serving for the passage of screws or nails which are driven into the panels or spacing element for the purpose of securing or clamping the panels in their spaced apart positions. In one convenient arrangement two sets of holes are formed through a cover piece, these holes being obliquely disposed so that screws or nails passed through said holes of one set will be driven diagonally into one panel or slab, and screws or nails passed through the holes of the other set will be driven into the other panel or slab, the effect of said screws being to draw the panels or slabs towards one another, the interposed spacing element serving correctly to space apart said adjacent panels or slabs relatively to one another during the erection or building of the wall or roof.

Preferably the mutually-opposed edges of the panels or slabs are chamfered on each side to provide accommodation at the joint in one wall for the correspondingly chamfered edge of a panel or slab of another wall in forming a three- or four-way junction. The angle of chamfer conveniently may be forty-five degrees and the arrangement such that the planes of chamfer intersect one another at the axis of the spacing element. Preferably said chamfer faces bed flat on to seating faces of the cover piece.

According to different embodiments of the invention the spacing element may be in the form of a loose piece suitably held in place whilst relatively positioning the panels, the cover piece being subsequently fitted, or said spacing element may be formed integral with the cover piece.

The cover piece may be formed with marginal portions adapted to overlap the panels or it may be formed to occupy the space formed by the chamfering of the panels so as to lie flush with the latter.

The preformed holes in the cover piece ensure that the screws or nails are driven in the desired direction and into the required part.

In one embodiment of the invention the spacing means consists of a separate tongue piece having the full height of the panels, and engaging into the adjacent edges of adjoining panels for mutual location and interlock of said panels. The tongue piece may consist of a bar which has a body portion of a thickness approximately equal to the width of the grooved panel edges at the head of the chamfer; that is to say, the panel edges are chamfered off to form edge faces having a width approximating the thickness of the bar. The bar is formed with centrally disposed projecting rib-like tongues by reduction of its thickness, said tongues being adapted to engage into the grooves of adjacent panels whilst the body portions of the bar bed on to the edge faces of the panels. In the case of a joint between two panels arranged in vertical coplanar relation, the bar will be formed with two tongues, these being disposed on opposite sides of the bar, and the cover pieces will be shaped to follow the contour of the joint so as to bed upon marginal face portions of the panels and upon the body portion of the bar. In cases where three, or four, walls meet at the joint, the bar may be of the above described form so that only two of the walls are tongue-engaged or the bar may have additional tongues corresponding in number and position with the said walls, and, in the case of the right-angular junctions, the cover pieces will bed only upon marginal portions of the panels in the locality of the junction.

Wall structures of practical form in accordance with the invention are illustrated in the accompanying drawings all of which are cross-sectional views showing joints in such structures. In the drawings

Figure 1 shows a joint according to one embodiment of the invention connecting panels arranged in coplanar relation.

Figures 2 and 3 respectively show a three-way and four-way joint according to the same embodiment of the invention.

Figure 4 shows a corner joint according to the same embodiment of the invention.

Figure 5 shows a joint according to another

embodiment of the invention and wherein a spacing element provided is integral with a cover piece, and

Figure 6 shows a modification of Figure 5.

In all of the constructions shown, the walls are composed of a series of panels or slabs, each of which conveniently may comprise a core 10 consisting of fibrous or other filling material bound with an inorganic binder such as a cementitious substance or with an organic binder such as synthetic resin, facing layers 11 of substantially rigid sheet material such as plywood or asbestos cement, and a surrounding wooden or other frame 12. However, the panels can be of any other convenient form provided that they have the required external configuration as herein-after set forth.

In the embodiment of the invention shown in Figures 1 to 4, the frame 12 of each panel is recessed on opposite sides to receive the facing sheets 11 so that the outer faces of said sheets 11 are flush with the outer faces of the frame. The frame is chamfered on each side to provide the bevel faces 13 and the outer face of the frame is formed with a centrally disposed groove 14.

In erecting the wall a spacing bar 15 is interposed between adjacent panels, said bar being formed with oppositely extending tongue portions 16 by reducing its thickness. Said tongue portions engage as a close fit into the panel frame grooves 14, the main body portion of the bar 15 constituting a spacing element between the panels. On the respective sides of the wall structure there are provided cover pieces each consisting of a strip 17 arranged to overlie the joint and having shoulder portions 18 adapted to bed on marginal face portions of the adjacent panels. Each cover strip extends the full height of the panels or the height of two or more courses of panels. Between said shoulder portions 18 the cover piece is formed with a wedge-like throat portion 19 having its sides inclined at 45 degrees to provide faces 20 adapted to bed flat on the chamfer surfaces 13 of the panels. The end face 21 of the throat portion is flat and is adapted to bed upon the body portion of the tongued bar 15. Thus the cover piece has intimate contact with all of the exposed faces of the parts in the locality of the joint. In each of the cover pieces 17 there are preformed holes. These holes pass through the cover piece from a central groove or recess 22 formed in the outer surface of said cover piece, and they comprise a series of holes 23 obliquely inclined in one direction so as to emerge from one of the inclined throat faces 20, another series of holes 24 obliquely inclined in another direction so as to emerge from the other inclined face 20 of the throat, the holes being perpendicular to said respective faces, and a central series of holes 25 extending perpendicular to the outer face of the cover piece. The inclined holes 23, 24 serve for the passage of screws 26 adapted to be driven into the respective panels, and the central holes 25 serve for the passage of screws 27 adapted to be driven into the body portion of the tongued bar 15.

The above described construction is such that the planes of the panel chamfer faces 13 intersect one another at the axis of the spacing bar 15.

The method of assembly consists in erecting one panel, placing the tongued bar 15 in position so that one of its tongues 16 engages into the groove 14 in the adjacent edge of the panel, placing the next panel in position so as to be engaged by the other tongue 16 of the bar, placing the

cover pieces 17 in position at the respective sides of the structure, passing screws 27 through the preformed central holes 25 in the cover pieces and driving them into the tongued bar 15 and then (or after completing these operations along the length of the wall) passing screws 26 through the inclined preformed holes in the cover strip and driving said screws into the frames of the panels.

Referring now to Figure 2, a joint between three walls meeting at a T-junction is formed as above set forth except that the cover piece is omitted where the third wall 26 meets the aligned walls. The chamfer faces 13 of the panel of said third wall approximately meet the adjacent chamfer faces 13 of the aligned panels. Right-angular quadrantal cover pieces 29 are provided for fitting into the corners between the third wall panel and the aligned panels, each of said quadrantal cover pieces having a series of preformed holes 30 emerging at the corner. Screws 31 which are passed through said holes are driven down through the joint between the meeting chamfer faces 13 of the panels so as to bite into said chamfer faces and said screws become driven into the body portion of the tongued bar 15. Screws 27 passed through the preformed holes 25 are driven through and beyond the bar 15 so as to become driven into the frame of panel 28.

In the case of the four-way wall junction shown in Figure 3, two of the opposite walls have their panel grooves 14 engaged by the tongued bar 15, and all cover pieces 29 are of right-angular quadrantal form, the screws 31 being passed through the preformed holes 30 in said cover pieces and biting into the chamfer faces 13 of the panels and screwing into the body portion of the tongued bar 15.

In forming a joint between two walls which meet one another at a right angle as shown in Figure 4, the tongued bar 15 is dispensed with and there is provided a cover piece 32 shaped to face off the corner in chamfered fashion, said cover piece having marginal shoulder portions 33 inclined at 45 degrees to bed on to marginal face portions of the panels, and having a right-angular wedge portion 34 on its inner face which fits into the space between the end faces of the panels. If so desired said wedge portion 34 may have tongues for engaging into the panel grooves. Preformed holes 35 for screws pass through the cover piece to enable screws 36 to be driven into the panels and other screws 37 to be driven through the joint between said panels and into a quadrantal cover piece 29 on the opposite side of the joint.

Where it is necessary to provide another structural element, such as a column, or door frame, in place of a panel, said element will be grooved and shaped as above described with reference to panel edges for enabling the joints to be formed in the manner above set forth, and cover pieces of suitably modified shape will be provided where level faces are not present. In other cases the cover pieces can be suitably formed to provide other structural parts such as a window head and sill.

It will be understood that the body portion of the tongued bar 15 determines the spacing apart of the aligned panels, and this ensures that in cases where another wall is to meet said aligned panels, the chamfer faces 13 of said other wall will properly meet and bed flat upon the chamfer faces 13 of the aligned panels. Moreover, building of the wall to accurate base line dimensions

will be ensured. The preformed holes ensure that the screws are driven in the required direction and into the proper part. The screws 26 (Figures 1 and 2) serve to draw the adjacent panels in a direction towards one another so that their chamfer faces 13 bed upon the inclined throat faces 20 of the cover piece. Likewise the screws 36 (Figure 4) draw the panels into position against the internal surface and wedge portion 34 of the corner cover piece. The screws 31 (Figures 2 and 3) which pass through the quadrantal cover pieces 29 bite into the chamfer faces 13 of the panels and draw the said cover pieces towards the spacing bar 15, thereby causing said cover pieces to exert firm clamping pressure on the panels; likewise the screw 37 (Figure 4) which is driven into the quadrantal cover piece 29, causes the latter to exert firm clamping pressure on the two panels meeting at a corner.

Referring now to Figure 5, the panels are formed as above described, but instead of a spacing bar being provided which is separate from the cover piece, said cover piece is formed integrally with an extending rib or stem 38 which enters the space between the opposed edges of adjacent panels and constitutes a spacing element. The said rib or stem 38 may be of such a length that the ribs or stems of identical cover pieces provided on opposite sides of the joint nearly meet one another as shown, but if there is such a cover piece on one side only of the joint then the rib or stem portion may be extended to occupy the whole of that space shown as occupied by the body portion of the spacing bar in Figure 2. The grooves 14 of the panel frames are unoccupied although they will serve to receive mastic waterproofing material if so desired. In erecting the wall the cover piece 17 is placed in position when bringing the panels into their proper relation, so that the rib or stem 38 will determine the space that is to exist between the said panels. As in Figures 1 and 2, the screws 26 passed through preformed holes 23, 24 will draw the panels properly into seating contact with the panel throat faces 20 and spacing rib or stem 38.

In the construction shown in Figure 6, which is a modification of that shown in Figure 5, the panel frame 12 has the same thickness as the core 10, so that the facing layers 11 overlie and are exposed at the sides of said frame. The cover strip 17 has a stepped configuration between its shoulder portions 18 and rib 38 to provide a parallel-sided throat portion 19 adapted to lie approximately in the plane of the facing sheets 11 of the adjacent panels or slabs and occupy the space which exists between the mutually opposed edges of said facing sheets, said throat portion having the same thickness as said facing sheets.

Two V-shaped grooves 39 are formed in the outer face of the cover piece, said grooves being equidistant from the centre line, and a series of preformed holes 40 adapted to receive fixing screws extends from the inner wall of each groove and obliquely across the cover piece and through the throat portion 19 thereof, the plane of the holes which extend from one groove intersecting the plane of the holes which extend from the other groove.

Preferably the cover portion of the strip is grooved as at 41 on its undersurface on each side of the throat portion. The construction is such that the underface of the throat portion 19 will bed down on to the side face of each panel frame and the shoulder portions 18 will bed down on to the outer surfaces of the panel facing sheets 11.

Screws passed through the preformed holes 40 and driven into the panel frames, have the effect of drawing the panels into their proper relative positions and securing them in such positions, as hereinbefore described with reference to the screws 26 (Figure 1).

In cases where necessary, particularly for roof work, bituminous or other waterproof gap-filling mastic substance may be packed into the joint, and those surfaces of the panels which are overlapped by the cover piece can be coated with such substance.

The cover piece in any of the constructions described can be formed in one piece or may be built up from separate parts of the same or different materials constituting the outer covering portion and the throat or in the case of Figures 5 and 6 constituting the outer covering portion, the throat and the rib respectively. An additional strip-like part of suitable form may be provided for covering the screw heads.

As a modification of any of the constructions described, the cover piece may have an outer or head portion which corresponds to the throat portion as hereinbefore described and has its outer surface flush with the outer faces of the panels so that an entirely flush joint results.

We claim:

1. In a building wall or the like, at least a pair of panels each having a marginal frame including an edge portion provided with convergently related inclined abutment faces and a central groove, a spacing bar of substantially cruciform cross section having opposite tongue portions fitting in the central grooves of adjacent frames and also having opposite strip abutment faces, a joint covering strip having its inner side provided with shoulder portions for overlapping contiguous areas of the panels and also having an intermediate throat portion adapted to fit substantially between the ends of adjacent frames, said strip having an outer face including a groove whose bottom corners are formed with oblique fastening applying surfaces which are disposed parallel to the convergently related abutment faces of the panel frames, whereby, a fastening piercing said fastening applying surfaces at right angles thereto also pierces and imbeds itself in said abutment faces, thereby firmly to clamp the strips and panels rigidly to the spacing bar.

2. In a building wall or the like, means for providing a secure joint between two or more panels, each having a marginal frame including an edge portion provided with convergently related inclined faces, comprising a centrally disposed bar of substantially cruciform cross section adapted to engage with said panel frames to form a joint, strips adapted to overlap parts of said panels, and fastening means for said strips adapted to secure the said panel frames and said centrally disposed bar together in their engaged positions to form the said joint.

3. In a building wall or the like, means for joining a plurality of panels together, each of said panels having a marginal frame including an edge portion provided with convergently related inclined abutment faces and a central groove, a spacing bar of substantially cruciform cross section having tongue portions adapted to fit into the central grooves of certain of said frames and also having abutment faces for engaging with the edge of certain of said frames, cover pieces adapted to overlap portions of said panels, and fastening members for said cover

pieces piercing and penetrating through adjacent portions of said panel frames and into portions of said spacing bar to thereby firmly secure the panels together.

4. In a building wall or the like, means for joining a plurality of panels together, each of said panels having a marginal frame including an edge portion provided with convergently related inclined abutment faces and a central groove, a spacing bar of substantially cruciform cross section having tongue portions adapted to fit into the central grooves of certain of said frames and also having abutment faces for engaging with

the edge of certain of said frames, said inclined abutment faces of each frame engaging with one contiguous inclined face of the next frame so as to form a continuous enclosing frame structure around said spacing bar with panels radiating therefrom in four directions, cover pieces adapted to overlap portions of said panels, and fastening members for said cover pieces adapted to penetrate into the said spacing bar to thereby secure the frame structure of the panels together.

BERNARD BRUNTON.
